UNITED STATES PATENT OFFICE.

WILLARD W. CHIPMAN, OF EVERETT, MASSACHUSETTS.

DOOR-HANGER.

SPECIFICATION forming part of Letters Patent No. 338,931, dated March 30, 1886.

Application filed September 19, 1885. Serial No. 177,513. (Model.)

To all whom it may concern:

Be it known that I, WILLARD W. CHIPMAN, a citizen of the United States, residing at Everett, in the county of Middlesex and State of Massachusetts, have invented a new and useful Improvement in Door-Hangers, of which the following is a specification.

My invention relates to certain improvements in that class of sliding doors which are suspended from bearings above the door; and the object of the invention is to provide improved means whereby the door may be easily opened and closed, and also a means for adjusting the door in case of any settling of the sill or floor.

The invention consists in certain details of construction and arrangements of parts more fully hereinafter described, and set forth in the claims.

Referring to the accompanying drawings, Figure 1 represents a door with my invention applied. Fig. 2 is a vertical section of the same. Figs. 3 to 8 are details of the various parts. Figs. 9 and 10 show a modification of the hanger.

A represents the side of a room, building, or railroad-car; A', the door-opening; and B, the door, shown partially open.

C is a way or track secured above the door-opening A', and D D are wheels running in the groove in the track C.

E is a bar, to the under side of which are secured two bearing-pieces, F F, each provided on its under side with recesses f f, in which travel the axle d of the wheel D, and also a chamber, f', in which the wheel D is free to work, and the inner ends are provided with mortises or recesses f'', in which is fitted the ends of a spacer, G, bolts or screws H H passing up through the bar E, thereby securing the parts together.

The wheel D may be grooved on the perimeter with the bearing-surface in the groove, in which case the track would have a raised center or tongue on which the wheel will move.

On the outside of each of the bearing-pieces F is a dovetailed piece, i, the lower end of which is provided with a boss, i', through which a screw, I, passes. J J are hangers provided with a recess, j, in the middle, the lower end of the opening being sufficiently wide to pass

over the dovetailed piece i on bearing-piece F, and the upper end of the opening is provided with dovetailed sides to correspond with the dovetails i, so that when the hanger J has been placed in position on the bearing-piece F it will be retained by the dovetails, and at the same time be free to be moved up or down.

The hanger J is provided at its upper end with a boss or projection, j', against which the upper end of the screw I bears, so that as the screw I is turned the hanger J will be raised or lowered. The lower end of the hanger J is provided with a bar, J', that projects inward, so as to be over the door, and is provided with two or more notches, j'', into which the hook K (see Fig. 6) is placed. The object of having more than one notch is that should the projection J' from any cause not be exactly over the center of the door-opening, then the hook K may be placed in one of the side notches, so as to make the door hang centrally. It will be seen that the door is thus adjustable both vertically and laterally. The lower end of the hook K is provided with a screw-thread, k, which is screwed down into the top of the door.

L, Figs. 1 and 8, is a scraper which may be secured to the ends of the bearing-pieces F, as shown, or to the ends of the beam E, the object of this scraper being to keep the track clear of any dust or mortar that may fall thereon, so as not to obstruct the wheels D.

The under side of the track C, I prefer to recess, as shown, so that the hook K may be passed over the projection J' when the latter is very near the under side of the track C.

In Figs. 9 and 10 I have shown a modification of the hanger J and hook K. In this case the lower end of the hanger J is formed with a flange, J'', in which is cut a groove or recess 90 to receive the head of the screw K'. The lower end of the screw K is provided with a nut, k'. In applying this arrangement to a door a recess is cut in the edge of the door for the admission of the nut k', and a hole is bored in the upper edge of the door for the screw to pass through into the nut k', by turning which the bolt is raised or lowered, as desired.

It will be seen that should the door require any adjustment it can easily be done by simply turning one or both of the screws I I up or down, as required.

What I claim as my invention is—

1. The combination of the bar E, bearing-pieces F F, provided with dovetailed projections *i* and screw I, the hangers J J, and hooks 5 K, with the wheels D, and track C, substantially as and for the purposes described.
2. The bearing-pieces F, provided with recesses *f*, *f'*, and *f''*, dovetail piece *i*, and screw I, in combination with the hanger J, having 10 recess *j*, with dovetailed edges for the adjustment of a door suspended therefrom, substantially as described and shown.
3. The hanger J, having a projection, *J'*, pro-

vided with notches *j''*, in combination with a hook, K, when used for supporting a door, substantially as shown and described.

4. The clearer L, in combination with the bearing-pieces F and track C, substantially as shown, and for the purpose described.

In testimony whereof I have signed my name 20 to this specification in the presence of two subscribing witnesses.

WILLARD W. CHIPMAN.
